UNITED STATES PATENT OFFICE

113,809

DESIGN FOR A DRESS

Jeanne Fields, New York, N. Y.

Application February 6, 1939, Serial No. 82,792

Term of patent 3½ years

To all whom it may concern:

Be it known that I, Jeanne Fields, a citizen of the United States and a resident of the city of New York, in the county of New York and State of New York, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1. The characteristic feature of my dress resides in the horizontal, graduated tucks, and spaced stitching in association with vertical front panels as shown.

I claim:

The ornamental design for a dress, substantially as shown and described.

JEANNE FIELDS.
